UNITED STATES PATENT OFFICE.

ARTHUR H. FRANKLIN, OF TRAVERSE CITY, MICHIGAN.

STEP-LADDER.

1,087,286.

Specification of Letters Patent.

Patented Feb. 17, 1914.

Application filed August 17, 1912. Serial No. 715,554.

To all whom it may concern:

Be it known that I, ARTHUR H. FRANKLIN, a citizen of the United States, residing in Traverse City, in the county of Grand 5 Traverse and State of Michigan, have invented a new and useful Improvement in Step-Ladders, of which the following is a specification.

This invention relates to step ladders specifically adapted to be used in orchards and on hill sides and uneven ground.

It embraces a step ladder proper, and hinged struts or legs therefor adapted to be extended at different angles to sustain the 15 ladder at greater or less heights as desired.

The legs or struts are independent of each other, and are both so attached to the ladder as to be capable of being extended from the ladder in any direction, front or side- 20 wise, so that they can be extended in opposite directions at the same time and each brace the steps against the other. In addition to these peculiarities, the construction is also adapted to lock the struts or legs 25 when extended in their extended positions.

The construction by which these results are attained, is fully set forth below.

In the accompanying drawing, Figure 1 30 is a rear elevation of the invention showing it erected on a side hill. Fig. 2 is an enlarged partial elevation showing the rear side. Fig. 3 is a section on the line 3—3 of Fig. 2. Fig. 4 is a section on the line 4—4 of Fig. 2.

35 Referring to the drawing, 5, 5 represents the risers and 6, 6 the treads forming the ladder portion of the device.

7 is the top or table of the ladder and as 40 shown it is broader and heavier than the steps 6. To this top or table, a swinging and swiveled metal frame is attached by vertical hook bolt 9. This frame is best shown at Fig. 2 and consists of a substan- 45 tially round and straight member 10 at the top, and a depending curved member 11 notched on the outer side and attached at either end to the outer ends of the straight member. The hook bolt 9 passes

50 partially around the part 10 and so that said bolt serves as a bearing to the member 10 permitting the frame to make complete horizontal turns on the bolt as an axis, and the bolt 9 also turns freely on its axis so that the frame is in effect swiveled to the top. 55 To prevent any movement by the swivel

frame lengthwise of the member 10, I provide the latter with an enlargement 10^a at the point where the hook bolt encircles it, and also provide such enlargement with an opening 10^b which is entered by the point 60 of the hook. The straight member 10 is also provided with integral lateral wings 13, 13 near its center and to these wings the legs or struts 15 are bolted firmly by bolts 14, 14. The wings are provided with elongated slots in which the bolts 14 are entered, and these slots allow the legs to move limited distances lengthwise after they are positioned, or when any weight is put upon the ladder. 65

70 While I have shown the invention applied to a step ladder in which the ladder portion consists of a stairway with flat steps or treads, it will be understood that such is the preferred construction, and that the invention may be applied to structures in which the steps of the ladder are simply rounds instead of flat steps. 75

For strength, I prefer to place around the ends of the top or table flat metal straps 80 20, and to secure the ends of such straps to the risers 5. The legs or struts are also attached to the notched member of the frame 8 by hook bolts 15 passing around the notched member, so that when the legs or 85 struts move by reason of the weight on the ladder, the bolts 14 will be forced to slide along the slots in the wings 13, and the bolts 15 will find seats in the notches of the notched member, and thus effect a locking 90 of the legs or struts in position.

95 My step ladder can be used in a great variety of positions, and with the legs ex- 100 tended in front or to either side, or in op- 105 posite directions. Being swiveled as stated, they are readily positioned or changed as desired, and usable on almost any kind of uneven or hilly ground.

It will be understood that the invention 100 can be used with any step ladder, the ladder of which is provided with rounds instead of steps.

I claim:—

1. The orchard step ladder having its struts or legs swiveled to the step ladder 105 proper upon a common vertical pivot.

2. The orchard step ladder having legs or struts hinged to the step ladder proper and also swiveled to it upon a common vertical pivot. 110

3. The orchard step ladder having struts or legs each independently adjustable, said struts being both hinged to the step ladder proper and also swiveled to it upon a common vertical pivot.

4. The orchard step ladder having its legs or struts swiveled to the step ladder proper upon a common vertical pivot, and also hinged to the ladder proper so that both 10 may be extended in front or sideways, in the same direction or in different directions.

5. The orchard step ladder having a step ladder proper, a frame swiveled to said step ladder proper upon a vertical pivot permitting the frame to make complete revolutions about the pivot, and legs or struts hinged to said frame and extensible in various directions from the same and means for locking the legs in their extended positions.

6. The orchard step ladder having a step ladder proper, a frame swiveled to said step ladder proper on a vertical pivot, legs or struts hinged to said frame and extensible 25 in various directions therefrom, and means whereby the legs or struts may be locked

in extended positions, said means including a notched surface on said frame.

7. An orchard step ladder having a step ladder proper, a frame swiveled to the top 30 of said step ladder proper about a vertical pivot, said frame having two arcuate notched portions, a pair of legs pivoted to said frame and extensible in various directions therefrom, and projecting elements on 35 said legs adapted to engage with said notched surfaces to thereby hold the legs in extended position, substantially as specified.

8. An orchard step ladder having a step 40 ladder proper, a frame swiveled to said step ladder, said frame having two arcuate notched portions, a pair of legs pivoted to said frame, the pivots being movable in said frame, and members on each of said legs adapted to coöperate and engage with said 45 notched portions to thereby hold the legs in extended positions, substantially as specified.

ARTHUR H. FRANKLIN.
